(57) **ABSTRACT**

A hydropower plant with offshore water supply includes at least one water intake structure, underground penstock, turbine, and tailrace. The water intake structure has a base built on a continental shelf of a water body and a water intake at an elevation above the base. The penstock has an inlet connected to the base and an outlet. The turbine is mounted on a turbine machine floor in an underground turbine room at an elevation lower than the base. The turbine has an inlet port connected to the penstock outlet and an outlet port connected to the tailrace. The inlet receives fluid from the water intake; the inlet port receives fluid from the outlet of the penstock; and the tailrace receives fluid from the inlet port and conveys the fluid to the water body.

3 Claims, 2 Drawing Sheets

FIG. 1

FIG. 2

HYDROPOWER PLANT WITH OFFSHORE WATER SUPPLY

BACKGROUND OF THE INVENTION

The present invention relates to energy production by hydropower and, more particularly, to a hydropower plant with an offshore water supply.

Current hydropower plants (impoundment, diversion, pumped storage) are dependent on a disruptable water supply. For example, river supplied water relies on precipitation (rainfall and snowfall), which is subject to droughts, and stored water supplies are vulnerable to overuse by diversions to agriculture and downstream city and habitat requirements.

As can be seen, there is a need for a hydropower plant having a water supply that is not disruptable by variations in precipitation and water use.

SUMMARY OF THE INVENTION

In one aspect of the present invention, a hydropower plant with offshore water supply comprises at least one water intake structure (10) having a base built on a continental shelf (24) of a water body and having a water intake at an elevation above the base; at least one underground penstock (12) having an inlet and an outlet, wherein the intake is coupled to the base of the at least one water intake structure (10); at least one turbine (16), mounted on a turbine machine floor (34) in an underground turbine room (14) having an elevation lower than the base, the at least one turbine (16) having an inlet port coupled to the outlet of the at least one underground penstock (12) and an outlet port; and a tailrace (28) coupled to the outlet port. The inlet fluidly communicates with the water intake; the inlet port fluidly communicates with the outlet of the at least one underground penstock (12); the tailrace (28) fluidly communicates with the inlet port; and the tailrace (28) is operative to convey fluid from the outlet port to the water body.

The hydropower plant disclosed herein has an uninterrupted water supply. The water supply has offshore water intake towers connected to underground penstocks, turbines, and a tailrace. The offshore intake eliminates the need for dams for impoundment, diversions, and pumped storage water supplies. The plant does not rely on precipitation; it relies only on the ocean as the unlimited water supply.

These and other features, aspects and advantages of the present invention will become better understood with reference to the following drawings, description, and claims.

BRIEF DESCRIPTION OF THE DRAWINGS

FIG. 1 is a schematic side view of a hydropower system according to an embodiment of the present invention; and FIG. 2 is a continuation thereof.

DETAILED DESCRIPTION OF THE INVENTION

The following detailed description is of the best currently contemplated modes of carrying out exemplary embodiments of the invention. The description is not to be taken in a limiting sense but is made merely for the purpose of illustrating the general principles of the invention, since the scope of the invention is best defined by the appended claims.

Broadly, one embodiment of the present invention is a hydropower plant with offshore water supply for power generation around the world. It does not produce greenhouse gases, dramatically reducing the environmental impact of energy production.

The hydropower plant of the present subject matter may be located anywhere having a water supply with a level that is not significantly affected by changes in precipitation, such as an ocean or other large water body, e.g., Lake Mead. The 10 plant may be manufactured and installed using well-known boring and mining methods.

Referring to FIGS. 1-2, an offshore hydropower plant is illustrated. The plant comprises water intake structures 10 similar to concrete intake structures/towers observable at 15 Lake Mead, rising from the continental shelf 24, that take in water near ocean level 22 and route the water into reinforced, underground penstocks 12. The penstocks 12 feed turbines 16 in an underground turbine room 14 having a turbine machine floor 34. As such, the turbines 16 have a 20 continuous flow of water that is not affected, or is only marginally affected, by changes in precipitation and water usage. The water drives the turbines 16, producing electricity that is collected via an existing electric grid and/or via a storage device (not shown). The penstocks 12 and a tailrace 25 28 exiting the turbine room 14 have cutoff valves 30, enabling an operator to control inflow and outflow through the turbines 16. The tailrace 28 is also supplied with a backflow preventer valve 32 to prevent water from reversing through the turbines 16. The turbine room 14 may be 30 accessed from a control room/visitors' center/employee entrance 18 via an access/construction tunnel/elevator 20. The tailrace 28 extends into the soil of the continental shelf 35 24, returning to the ocean up slope 26 above and beyond the initial intake structures 10. Alternatively, the tailrace 28 may deliver the outflow to a pump storage system or reservoir.

It should be understood, of course, that the foregoing relates to exemplary embodiments of the invention and that modifications may be made without departing from the spirit and scope of the invention as set forth in the following 40 claims.

What is claimed is:

1. A hydropower plant with offshore water supply, comprising:
at least one water intake structure (10) having a base built on a continental shelf (24) of a water body and having a water intake at an elevation above the base;
at least one underground penstock (12) having an inlet and an outlet, wherein the inlet is coupled to the base of the at least one water intake structure (10);
at least one turbine (16), mounted on a turbine machine floor (34) in an underground turbine room (14) having an elevation lower than the base, the at least one turbine (16) having an inlet port coupled to the outlet of the at least one underground penstock (12) and an outlet port; and
a tailrace (28) coupled to the outlet port;
wherein the inlet fluidly communicates with the water intake; the inlet port fluidly communicates with the outlet of the at least one underground penstock (12); the tailrace (28) fluidly communicates with the inlet port; and the tailrace (28) is operative to convey fluid from the outlet port to the water body; and
wherein a first cutoff valve (30) is mounted in the at least one underground penstock (12) and a second cutoff valve (3) is mounted within the tailrace (28).
2. A hydropower plant with offshore water supply, comprising:

at least one water intake structure (10) having a base built on a continental shelf (24) of a water body and having a water intake at an elevation above the base;
 at least one underground penstock (12) having an inlet and an outlet, wherein the inlet is coupled to the base of the at least one water intake structure (10);
 at least one turbine (16), mounted on a turbine machine floor (34) in an underground turbine room (14) having an elevation lower than the base, the at least one turbine (16) having an inlet port coupled to the outlet of the at least one underground penstock (12) and an outlet port; and
 a tailrace (28) coupled to the outlet port;
 wherein the inlet fluidly communicates with the water intake; the inlet port fluidly communicates with the outlet of the at least one underground penstock (12); the tailrace (28) fluidly communicates with the inlet port; and the tailrace (28) is operative to convey fluid from the outlet port to the water body;
 wherein the tailrace (28) further comprises a backflow preventer valve (32).

3. A hydropower plant with offshore water supply, comprising:

at least one water intake structure (10) having a base built on a continental shelf (24) of a water body and having a water intake at an elevation above the base;
 at least one underground penstock (12) having an inlet and an outlet, wherein the inlet is coupled to the base of the at least one water intake structure (10);
 at least one turbine (16), mounted on a turbine machine floor (34) in an underground turbine room (14) having an elevation lower than the base, the at least one turbine (16) having an inlet port coupled to the outlet of the at least one underground penstock (12) and an outlet port; and
 a tailrace (28) coupled to the outlet port;
 wherein the inlet fluidly communicates with the water intake; the inlet port fluidly communicates with the outlet of the at least one underground penstock (12); the tailrace (28) fluidly communicates with the inlet port; and the tailrace (28) is operative to convey fluid from the outlet port to the water body; and
 further comprising an onshore entrance structure (18) coupled to the turbine room (14) via an access way (20).
